DESIGN FOR A LACE TRIMMING OR SIMILAR ARTICLE

Ernest W. Freudenberg, Larchmont, N. Y.

Application May 3, 1940, Serial No. 92,096

Term of patent 3½ years

To all whom it may concern:

Be it known that I, Ernest W. Freudenberg, a citizen of the United States, residing in Larchmont, New York, county of Westchester, State of New York, have invented a new, original, and ornamental Design for a Lace Trimming or Similar Article, of which the following is a specification, reference being had to the accompanying drawing forming a part thereof.

The figure of the drawing is a plan view of a lace trimming showing my new design.

I claim:

The ornamental design for a lace trimming or similar article, as shown.

ERNEST W. FREUDENBERG,
